APPARATUS FOR RECORDING AND
REPRODUCING SOUNDAdolph A. Thomas, New York, N. Y., assignor to
Radio Corporation of America, New York,
N. Y., a corporation of Delaware

Application October 10, 1929, Serial No. 398,675

31 Claims. (CL 178—100.3)

My invention is for novel methods and means for recording and reproducing sound through the medium of photographic film. One of the main objects of this invention is to provide a household phonograph in which a long-playing film record controls the operation of electric reproducing mechanism.

The wax disk records used almost universally in phonographs since the first days of the industry are highly objectionable for several reasons. From the standpoint of the user, the main drawback of the old phonograph records is their limited capacity, which necessitates frequent changing of records. That is a nuisance and annoyance to everybody. Attempts have been made to overcome this objection by installing automatic record-changing mechanism in phonographs, but all such mechanisms are necessarily complicated and greatly add to the cost of the machine.

Among other undesirable characteristics of ordinary phonograph records, I may mention that they break easily, are expensive to ship because of their weight and fragility, and their useful life is very short. While the new electrical recording methods and pickups have generally improved the quality of music to be obtained from existing phonographs, the fact remains that the use of a needle has certain inherent drawbacks. There is, for instance, the ever-present needle scratching which becomes more pronounced with each playing of the record. Then, needles must be frequently changed, usually for each record, and that is a task which nobody likes.

The foregoing and other objections and disadvantages in the old-type phonographs do not exist in the improved film phonograph of my invention. I use a photographic film on which sound waves have been recorded in a series of parallel tracks running in alternately opposite directions. At least four such tracks are recorded on each length of film, but it is possible to have six, eight and even more sound tracks on one film if it is wide enough. A film record of that kind has an enormous acoustic capacity and can play continuously for one or more hours, in accordance with the length of the film, which may vary from a hundred feet to a thousand and upwards.

The reproducing mechanism of my new film phonograph comprises a rotary shutter disk having a slot for each sound track on the film. These shutter slots permit the passage of light rays through the film to a photo-electric cell which controls a suitable loudspeaker system. When

the end of a sound track is reached, the film-driving connections are automatically reversed and the shutter disk is rotated to move the next slot into line with the next track. These operations are automatically repeated until the end of the last sound track is reached, whereupon the film automatically stops. The final winding of the film on the initial pay-out reel leaves it in condition for the next playing.

I use the film itself for controlling the film-reversing mechanism by photo-electric means which eliminate all mechanical contact with the film. Near each end of the film, at a suitable distance from the adjacent ends of the sound tracks, is a slot or small aperture through which light passes to a photo-electric cell when the end of a sound track is reached. The illuminated cell instantly closes a circuit which operates certain electromagnetic devices for reversing the film-driving connections and moving the shutter disk. These things will be fully explained later on.

The film in my new phonograph is supported by a pair of spools, which are preferably mounted on top of the cabinet in horizontal position for easy insertion and removal. The supporting pins for the reels are arranged on opposite sides of a box which contains the photo-electric cells of the reproducing mechanism. It is a simple matter to thread the film from the pay-out reel through the photo-electric control box and onto the take-up reel. This requires no more skill than loading of a home movie camera with which many people are familiar. After a film has been inserted, the phonograph is started by simply pressing a button, and the playing continues without further attention until the last sound track is run off, whereupon the machine stops itself. If a person wants to stop the phonograph before the end of the film is reached, he need only push a "stop" button mounted on the top board or in any other convenient place.

The novel features and practical advantages of my invention will be understood from a detailed description of the accompanying drawings, in which—

Fig. 1 shows a perspective of a film phonograph embodying my invention;

Fig. 2 is an enlarged sectional view on line 2—2 of Fig. 1, through the photo-electric control box;

Fig. 3 represents a top plan view of Fig. 2, with the cover of the box removed;

Fig. 4 shows diagrammatically four different positions of the rotary film shutter;

Fig. 5 is a face view of the film shutter and a

- portion of the associated film, this view being taken on section line 5—5 of Fig. 2;
- Fig. 6 shows a side view of the shutter-operating mechanism on line 6—6 of Fig. 2;
- 5 Fig. 7 represents a side view of a contact wheel movable with the film shutter for controlling certain electrical connections, this view being a section on line 7—7 of Fig. 2;
- Fig. 7a is an edge view of Fig. 7;
- 10 Fig. 8 is a detached perspective of certain parts of the shutter-actuating device;
- Figs. 9 and 10 show the two ends of a film bearing four record tracks running in alternately opposite directions;
- 15 Fig. 11 represents a sectional front view of the operative mechanism in the cabinet, this view being partly diagrammatic to show the circuits that control the film-driving connections and the shutter-actuating device;
- 20 Fig. 12 is an enlarged sectional view through a portion of the photo-electric control box to show the mounting of the film behind the slotted shutter disk;
- Fig. 12a (on the second sheet) is a face view of the 25 hinged film gate in the control box, this view being taken on section line 12a—12a of Fig. 12, but on a smaller scale;
- Figs. 13 and 14 are detached detail views of the 30 mounting for the hand switch lever shown in Fig. 11, these two views being at right angles to each other;
- Fig. 15 illustrates an enlarged front view of the 35 hand switch and associated connections; and
- Fig. 16 and 17 show modified forms of hand 40 switches for starting and stopping the machine.
- The operative mechanism is housed in a cabinet 10 of suitable size and design. On the top board 12 is a pair of reels 13 and 14 for operatively supporting a photographic film 15 on which sound 45 has been recorded in a plurality of tracks. A box 16 mounted on the top board 12 between reels 13 and 14 contains photo-electric mechanism controlled by the different record tracks on the film. For convenience I shall refer to box 16 as the 50 control box. Below the top board 12 is a chamber closed by doors 17, and the lower portion of the cabinet contains suitable reproducing apparatus, including a loudspeaker. It may be assumed that the sound from the loudspeaker issues 55 through the large front opening 18, which is covered by an ornamental grille. The space back of the doors 17 may also contain the necessary vacuum tubes and other devices that go to make up an electric amplifying system for converting the light impulses in box 16 into electric 60 impulses for operating the loudspeaker.
- The control box 16 is placed over an opening 19 in top board 12 and secured in any practical way, as by screws 20 passing through ears or 65 lugs 21 at the bottom edge of the box. It is convenient to make this box of sheet metal in two sections connected at the adjacent walls 22 and 23, which thus constitute a transverse partition. The two sections of box 16 provide a large chamber 24 and three smaller chambers 25, 26 and 27, which are formed by a pair of partitions 28 arranged at an angle so that the central chamber 25 is considerably wider at one end than at the other. The partitions 28 may be shaped from a 70 single piece of sheet metal secured in place by rivets 29 or otherwise. The inside of box 16 is made light-proof by painting the walls black or lining them with black material. The top of box 16 is closed by two covers 30 and 31 hinged at 32.
- 75 If desired, a single cover may be used for both sections of the box, but the advantage of two separate covers is that either section of the box may be opened for inspection while the other section remains closed. Furthermore, in threading the film through box 16, it is convenient to throw the front cover 31 back on the rear cover 30.
- The film 15 passes through slits 33 in the sides of the control box 16 and through end slits 34 in partitions 28, as shown in Fig. 3. Between the 10 film reels 13—14 and the control box are the usual sprocket wheels 35 and 36 for driving the film from one reel to the other at correct uniform speed. At the same time the sprocket wheels hold the film taut in alignment with the 15 slits 33 and 34 in control box 16. These slits extend to the top of the box, so that it is a very simple matter to insert the film after the cover 31 has been thrown back. The exposed side of wall 22 is preferably lined with soft textile material 20 having no abrasive action on the moving film. The partition 23 carries a flat frame 31 to which a gate 38 is hinged at 39. A spring-pressed latch 40 pivoted at 41 to the top of gate 38 engages a hook 42 on partition 23 to hold the gate firmly 25 in normal closed position. By simply pressing down on the extension 43 of latch 40, the latter is easily released from hook 42 to permit swinging of gate 38 to open position, as indicated by the dotted lines 38' in Fig. 2. The inner face of 30 gate 38 carries a pair of light leaf springs 44 arranged to press gently against the film 15 at its top and bottom edges, as best shown in the enlarged view of Fig. 12. A vertical slot 45 in gate 38 is in alignment with a similar slot 46 in the 35 transverse partition 22 of box 16. The rollers 35' and 36' associated with sprocket wheels 35 and 36 are so mounted that they can be moved aside to permit threading of the film through the control box. It is not necessary to show the 40 adjustable mounting of rollers 35' and 36', because that forms no part of my invention and is a detail usually found in motion picture cameras and projectors.
- The bottom plate 47 of control box 16 carries a 45 U-shaped supporting bracket indicated as a whole by 48. This bracket, which may be a single casting of aluminum or a molding of bakelite, comprises a pair of depending side walls 49 and 50 connected at the bottom by a cross-piece 51. A horizontal shaft 52 journaled in the side walls 49 and 50 carries at one end a hub or short sleeve 53 to which a rotary shutter disk 54 is secured by screws 55 or otherwise. One face of disk 54 is preferably covered with a lining 56 of soft light-proof material, like black velvet, felt, silk, and the like. The transverse partition 23 in box 16 is cut away or shaped to provide a recess 57 for receiving the rotary shutter disk 54, which extends into the control box through a bottom 60 slot 58. Referring to Fig. 12, it will be seen that disk 54 is mounted as closely as possible to the transverse wall 22, so as to cover the slot 46. The weak springs 44 hold the film 15 pressed gently against the cloth surface 56 of disk 54, 65 whereby a light-proof contact is established between the film and the disk with a minimum amount of friction. The interposed lining 56 prevents injury to the moving film. In the present embodiment of my invention, I have assumed 70 by way of illustration that the film 15 is provided with four record tracks A, B, C and D running in alternately opposite directions.
- Referring to Figs. 9 and 10, we shall assume 75 that 59 is the initial pay-out end of the film and

68 the final wind-up end. Accordingly, the first sound track A begins at 61 and the film is first played by running it in the direction of arrow 62. In other words, when the film is first placed in the machine, it is mounted on reel 13, which is thus the initial pay-out reel, and 14 is the initial take-up reel on which the film is wound during the playing of sound track A. When the end 63 of sound track A is reached, the film is automatically 10 reversed (by mechanism to be described later on) and runs in the direction of arrow 64. The beginning of track B is at 65 in Fig. 10 and the end at 66 in Fig. 9. When the end of the second track B is reached, the driving connections 15 of the film are again reversed and the film is again wound off reel 13 onto reel 14 to play the third record track C, which begins at 67 in Fig. 9 and ends at 68 in Fig. 10. The film is now once 20 more reversed and is wound off reel 14 onto reel 13 during the playing of the last sound track D, which begins at 69 in Fig. 10 and ends at 70 in Fig. 9. It will therefore be clear that the four record tracks A, B, C and D constitute 25 in effect one continuous track which begins at 61 and ends at 70.

The chamber 24 of control box 16 contains an electric lamp 71 mounted on a base 72 in line with the vertical slot 46 of partition 22. If desired, a shield or reflector 73 may be used with lamp 71 to direct the light toward slot 46, which is sufficiently tall to encompass the width of the film, so that the light may strike any one of the record tracks. It is assumed that the lamp 71 is connected to a source of substantially constant 30 current or potential, so as to give a uniform light of the required intensity. The lamp 71 will usually be connected to the house-lighting system. If the latter uses alternating current, a suitable rectifier is interposed. In chambers 25, 40 26 and 27 of control box 16 are mounted three photo-electric cells 74, 75 and 76. Several types and makes of photo-electric cells suitable for the present purpose are obtainable in the open market, and it will therefore not be necessary to 45 show or describe any structural details of these cells. For the purpose of this description, it is sufficient to say that each photo-electric cell has an anode and a light-sensitive cathode adapted to project a stream of electrons to the anode 50 under the action of light. As is well known, the intensity of the electron stream depends on the quantity of light or degree of illumination that reaches the cathode. The photo-electric cells 74, 75 and 76 are each supported on a base 77 at- 55 tached to the bottom of the control box 16. On either side of the electric lamp 71 are two mirrors 78 and 79 arranged at such an angle as to reflect light from lamp 71 to the photo-electric cells 75 and 76, respectively, as indicated diagrammatically by the dash-dot lines 80 and 81 in Figs. 3 and 11. The mirrors 78 and 79 are rigidly held in frames 82 fixed to the bottom plate 47 of control box by screws 83, or otherwise. One of the screws 83 of each frame 82 may pass through a slot 84 curved about the other screw as a center 60 to permit adjustment of the frames to the correct angle. The light reflected from mirror 78 reaches the photo-electric cell 75 through aligned apertures 85 in partitions 22 and 23, and the light 65 reflected by mirror 79 passes through similar apertures 86 to the photo-electric cell 76 in chamber 27. For convenience I shall refer to the aligned slots 85 as a single slot, and the same applies to the two slots 86.

75 The light that strikes the cathode 74' of the

photo-electric cell 74 from lamp 71 is controlled not only by the record tracks A—D of film 15, but also by the rotary shutter disk 54. It is essential that only one record track be exposed to the light at one time, and this is accomplished 5 by means of radial slits in disk 54, as best shown in Fig. 5. Since the film 15 in the present case bears four sound tracks, the disk 54 has four slits a, b, c and d. These slits are not only spaced from each other angularly, but are also displaced 10 in a radial direction to correspond to the position of the sound tracks on the film. Although only a single set of slits a—c is necessary in disk 54, I prefer to have more than one set in order to diminish the angle through which the disk must 15 be moved to bring successive slits into operative position in relation to the film. The disk shown in the drawings has three sets of slits a—d. We may assume in Fig. 5 that the imaginary vertical line 87 represents the operative position of the 20 slits in the shutter disk 54, which is here shown with slit a in operative position to permit the passage of light through sound track A. The vertical length of the shutter slits is such as to permit a thin band of light to strike the sound track 25 transversely across its entire width.

The different operative positions of shutter disk 54 are diagrammatically illustrated in Fig. 4. When the disk is in position 54a, slit a is in line with sound track A of the film. In position 54b 30 of the disk, slit b is in line with sound track B, and when the disk is in position 54c, slit c permits the passage of light through sound track C. In the final position 54d of the shutter disk, slit d is in line with the last sound track D of the film. 35 The lining 56 of disk 54 is cut away at 88 opposite each slit, so as not to obstruct the passage of light. Since the disk 54 in the present instance has twelve slits, it must be moved through an angle of thirty degrees to bring the next slit into 40 operative position. The movement of the shutter disk from one slit to the next is automatically accomplished when the end of a record track is reached. I shall now proceed to describe the 45 shutter-actuating mechanism.

The shaft 52 which carries shutter disk 54 has a ratchet wheel 89 fixed thereon, and this ratchet wheel is operated by a pawl 90 pivoted on a pin or screw 91 projecting from a disk 92. The latter is disconnected from shaft 52 and is normally 50 held against a fixed stop 93 by a contracting coil spring 94. One end of this spring is connected to a lug 95 projecting upward from the bottom plate 47 of box 16, and the other end of the spring is attached to a projection 96 on disk 92. The 55 various parts mounted on shaft 52 extend into chamber 24 through an opening 97. The shaft 52 also carries a locking wheel 98 provided with peripheral notches 99 arranged to be engaged by a latch member 100. A spring arm 101 attached to a fixed bar or bracket 102 normally presses the pointed end of latch member 100 into one of the notches 99 of locking wheel 98. The supporting part 102 may be a cross-bar or strip 60 attached to the sides 48 and 50 of frame 48, as shown in Fig. 2. The number and spacing of the locking notches 99 correspond to the arrangement of slits a—d in shutter disk 54. Since the disk in the present case has twelve slits arranged equidistantly apart, there are twelve notches 99 spaced evenly around the edge of wheel 98. When the latch member 100 engages one of the notches 99, the shutter disk 54 is locked in such 70 position that one of the slits a—d is in operative 75

relation to the corresponding sound track of the film.

Next to the locking wheel 98 on shaft 52 is an insulating disk 103 which always turns with the shaft. The disk 103 has three contact pieces 104 evenly spaced, so that their angular positions correspond to the three slits *d* of shutter 54. The disk 103 may be molded of bakelite or other composition material, and the contact pieces 104 10 may be strips of brass embedded in the material during the molding operation. Two insulated switch arms 105 and 106 are mounted on cross bar 102, which may be of insulating material. The switch arms 105-106 15 may be a pair of spring blades pressing against the periphery of the insulating disk 103. Whenever the switch arms 105-106 engage one of the contact pieces 104 of disk 103, they are electrically connected to control a circuit for stopping the film, as will presently be explained in detail. The arrangement of 20 switch arms 105-106 is such that they engage one of the contact pieces 104 whenever a slit *d* of the shutter disk 54 is in the position of line 87 (see Fig. 5) to control the last sound track *D* 25 of film 15.

An arm 108 is pivoted on a rod 109 supported between the side walls 49 and 50 of bracket 48. A vertical link 110 is pivoted to the free end of arm 108, and this link has a slot 112 at its upper end to receive a pin 113 projecting laterally from disk 92. A contracting coil spring 114 normally holds the lower end of slot 112 against pin 113. One end of spring 114 is attached to a lug 115 projecting from the bottom plate 47 of box 16, and 30 the lower end of the spring is fastened to a pin 116 of link 110. Since the disk 92 is normally held against the fixed stop 93 by spring 94, the pin 113 constitutes a stop for the normal raised 35 position of the pivoted arm 108. A solenoid core 40 117, pivotally supported from a pin 118 on arm 108, extends into a hollow coil 119. A lateral pin 120 on the free end of arm 108 supports a dog 121, which is normally held against a stop 122 on arm 108 by a light coil spring 123, which is 45 attached at one end to the arm and at the other end to the dog by pins or screws 124 and 125. The free end of dog 121 normally engages the tip of a bevelled extension 126 on latch member 100, as shown in Figs. 6 and 8. The cross-pin 120 50 on the free end of arm 108 may also be used as a pivot for link 110.

When the solenoid coil 119 is energized, the arm 108 is pulled down through a fixed angle. The first thing that happens when the arm 108 55 begins to move down is the unlocking of shaft 52 (and all parts mounted thereon), by the dog 121 forcing the latch member 100 out of engagement with the notched wheel 98. This unlocking takes place before the upper end of slot 112 in link 110 60 strikes the pin 113 of disk 92. In other words, the slot 112 permits the unlocking of shaft 52 before the arm 108 becomes coupled to the pawl disk 92, which is loose on the shaft. When the upper end of slot 112 strikes the pin 113, the 65 continued downward movement of arm 108 under the action of coil 119 rotates the disk 92 and causes the pawl 90 to operate the ratchet wheel 89 fixed to shaft 52. The pivotal mounting of link 110 allows the same to accommodate itself to the circular path of pin 113 during the rotation 70 of disk 92. As I said before, the arm 108 is actuated by coil 119 through a predetermined angle, which is so calculated that the shutter disk 54 is rotated through an angle equal to the distance 75 between a pair of slits. In other words, every

time the coil 119 is energized, the shutter disk 54 is given a kick that brings the next slit into line with its associated record track on the film.

Before the solenoid arm 108 reaches the end of its downward movement, the pivoted dog 121 snaps out of engagement with the bevelled extension 126 of latch member 100, so that the latter is instantly thrown back against the periphery of wheel 98 by spring arm 101. When that occurs, the latch member 100 strikes the 10 wheel 98 at some point between two notches, so that the rotation of the wheel by the continued downward movement of arm 108 is not prevented. The frictional engagement between the periphery of wheel 98 and the tip of latch mem. 15 100 is not sufficient to interfere with the rotation of shutter shaft 52 by arm 108. When this arm reaches the limit of its downward movement, the next notch 99 of wheel 98 registers with latch member 100, whereupon the latter 20 automatically snaps into locking engagement and holds the shutter disk 54 in correct position. After the shutter disk has thus been moved to its new position, coil line 119 is de-energized and the tensioned coil spring 114 pulls the arm 108 25 back to normal raised position. During the return movement of arm 108, the free end of dog 121 rides under the tip of latch extension 126. Just before the arm 108 reaches the end of its return movement, the dog 121 moves over the end 30 of extension 126, whereupon the spring 123 pulls the dog back to normal position against the stop 122. Since the wheel 98 is locked before the arm 108 begins its return movement, the ratchet wheel 89 remains fixed while the pawl 35 90 slides over the teeth during the return of disk 92. All the parts are now ready to repeat the operation above described when the coil 119 is again energized.

I shall now describe the driving connections 40 for the film and the means by which those connections are automatically reversed at the end of each sound track. The film-driving sprockets 35 and 36 are fixed on a pair of rotary shafts 45 127 and 128 which extend vertically below the top board 12 of the cabinet, as shown in Fig. 11.

The lower end of sprocket shaft 127 is supported in a bracket 129 carried by a horizontal partition 130 in the cabinet. A bracket 131, also fixed on partition 130, has two vertically aligned bearings 132 and 133 for supporting the sprocket shaft 128. The upper portions of sprocket shafts 127 and 128 pass through bearings in (or supported by) the top board 12. Two bevel gears 134 and 135 are loosely mounted on shaft 128 and 55 mesh with a bevel gear 136 fixed on a shaft 137, one end of which is supported in bracket 131 and the other end in a bracket 138. A small electric motor 139, supported on partition 130, has a driving shaft 140 which carries a worm 141 permanently in mesh with a worm gear 142 fixed on the countershaft 137.

A clutch ring 143 is keyed on sprocket shaft 128, so as to be slidable into engagement with the teeth of either bevel gear 134 and 135. An annular groove on clutch ring 143 receives the forked end of an operating lever 144, according to the usual practice. The lever 144 is pivoted at 145 on a suitable support (not shown), and the free end 146 of the lever is in the form of (or otherwise carries) an armature arranged to operate between a pair of electromagnetic coils 147 and 148. A contracting coil spring 149 is connected at one end to a fixed point 150, and at the other end to a point 151 on lever 144. The arrange- 70 75

ment of spring 149 is such that it holds the clutch lever 144 in either of its actuated positions. When coil 147 is energized, the clutch ring 143 is moved into operative engagement with bevel gear 134 to rotate the sprocket shafts 127 and 128 in a direction to unwind the film from reel 13 onto reel 14. This may be called the forward movement of the film, as indicated by the arrow at the top of Fig. 11. When the opposite coil 148 is energized, the lever 144 is rocked the other way to throw the clutch ring 143 into engagement with bevel gear 135, whereby the rotation of the film is reversed, so that it is unwound from reel 14 onto reel 13. The transmission connections between the motor shaft 140 and the sprocket shafts 127-128 are made to run as silently as possible.

The film reels 13 and 14 are mounted on a pair of stud-shafts 152 and 153, which may be journaled in the top board 12, or otherwise suitably supported. A pivoted weight 154 at the upper end of each reel shaft permits the easy insertion and removal of the reels, and at the same time holds them against vertical displacement during the operation of the machine. A grooved pulley 155 is mounted on the lower end of reel shaft 152, and a similar pulley 156 is carried by the lower end of reel shaft 153. The sprocket shafts 127 and 128 are provided with grooved pulleys 157 and 158, respectively. The aligned pulleys 155 and 157 are connected by a driving band or belt 159, and a similar belt 160 connects the pulleys 156 and 158. The driving belts 159 and 160 are preferably of elastic material, like rubber, finely wound coil springs, rubberized fabric, and other material suitable for the purpose. The tension of belts 159 and 160 is such that they permit slipping of the pulleys to allow the reels 13 and 14 to accommodate themselves to variable speeds during the winding and unwinding operations. A belt or chain 161 connects the sprocket shafts 127 and 128 for simultaneous operation at the same speed.

The gear reduction between the motor shaft 45 140 and the sprocket shafts 127-128 is such that the film is moved at the proper linear speed through the photo-electric control box 16. The speed of the film during the reproduction should be substantially the same as the speed used in 50 the recording operation. It is understood that the speed of the film across its optical field should be uniform, and it is therefore necessary that the motor 139 operate at constant speed. The rate at which the film is paid out from one reel 55 and wound onto the other will vary continuously during the movement of the reels, but the rectilinear speed of the film through the control box is constant. For this reason it is necessary to have a certain amount of play in the film between each reel and the adjacent sprocket wheel. This is usually accomplished by a so-called looping of the film, as may be found in every motion 60 picture camera and projector. I have not deemed it necessary to show the looping of the film, because it is a detail well understood and its omission simplifies the drawings.

If we assume the reel 13 to be the initial payout reel, the other reel 14 becomes the driving reel during the playing of sound tracks A and C, and 65 is positively actuated through belt 160 to pull the film off reel 13. During this forward drive of the film, the belt connection 159 between shafts 127 and 152 allows the rotation of reel 13 at varying speeds for the unwinding of the film, 70 while the sprocket shaft 127 rotates at constant

speed. When the film is wound off reel 14 onto reel 13 during the playing of sound tracks B and D, it is reel 13 that is positively driven, and reel 14 allows the film to be pulled off as required. I may incorporate into the machine a suitable 5 arrangement for automatically tightening the belt 160 when reel 14 takes up the film during the playing of sound tracks A and C, and tightening the other belt 160 when reel 13 takes up the film for sound tracks B and D. An automatic belt- 10 tightening device suitable for that purpose is disclosed in my copending application Serial Number 351,240.

Referring to Figs. 11, 13, 14 and 15, there is a hand lever 162 projecting through a slot 163 in top board 12. This lever or finger piece is pivoted on a pin 164 carried by a bracket or block 165, which may conveniently be attached to the underside of the top board. The lever 162 carries a spring-pressed ball or button 166 adapted to snap 20 into recesses 167 and 168 in bracket 165 for frictionally holding the lever in either of two actuated positions. When the lever 162 is vertical, as shown in dotted lines in Fig. 13 and in full lines in Fig. 15, the button 166 is held pressed in 25 recess 167. When the lever 162 is in the "stop" position 162a (see Figs. 13 and 15), the button 166 is forced into recess 168. The lower extension 169 of finger piece 162 is arranged to actuate a pair of spring arms 170 and 171. The spring 30 arm 170 is mounted at its lower end on a suitable support 172 and is provided near its upper end with a bevelled catch 173. An arm or lever 174 pivoted at 175 carries an armature 176 in operative relation to electromagnet 177, or the arm 35 itself may be magnetic. A contracting coil spring 178 normally holds the arm 174 against a fixed stop 179. One end of spring 178 is connected to arm 174 and the other end may conveniently be attached to the bracket 165. When the arm 174 40 is in normal raised position against stop 179, the free end of the arm is above the bevelled catch 173. When the coil 177 is energized, the arm 174 is pulled down into the position indicated at 174', and catch 173 locks the arm in that position. 45 When the hand lever or finger piece 162 is moved into the "start" position indicated by dotted lines 162b, the extension 169 moves the locking spring 170 into position 170', whereby the solenoid lever 174 is released and quickly pulled back to 50 normal position by spring 178.

Still referring to Fig. 15, the spring arm 171 is normally in contact with an adjacent spring arm 180. These two arms are mounted on an insulating support 181 and constitute a normally 55 closed switch in the circuit of the electric motor 139, as I shall presently explain. The solenoid lever 174 is operatively connected to switch arm 180 through an insulating piece 182, which is attached to both of those parts. As long as the 60 member 174 is held in raised position by spring 178, the connecting piece 182 holds the switch arm 180 pressed against the associated arm 171 to close the motor circuit. When the coil 177 is energized and pulls down the arm 174, the connected switch member 180 is pulled down away from switch member 171, so that the motor circuit is broken. The open position of switch member 180 is indicated by the dotted lines 180'. It will thus be seen that, as long as the solenoid 70 arm 174 is held locked in position 174' by catch 173, the motor circuit remains open. When the finger piece 162 is moved to "start" position 162b, the arm 174 is released and the motor switch 171-180 is automatically closed. By moving the 75

finger piece 162 to "stop" position 162a, the extension 169 engages the free end of spring arm 171 and raises the latter into position 171' to open the motor circuit. It should be noted that the finger piece 162 is locked in "stop" position 162a, so that the motor circuit remains open until the finger piece is moved to normal vertical position. However, when the finger piece 162 is moved to "start" position 162b for closing the motor circuit, the spring arm 170 moves the finger piece to normal vertical position as soon as it is released. In other words, when a person wants to start the machine, he simply moves the finger piece 162 to position 162b and then lets go.

15 I now come to the circuit connections in Fig. 11. One side of the motor is connected to a supply main 183 attached to a plug 184, which is intended to be inserted in an ordinary house-lighting socket. The other side of the motor is connected by conductor 185 to switch arm 171. The adjacent switch arm 180 is connected by a conductor 186 to the other service main 187. The rectangular outline 188 indicates diagrammatically any suitable form of electric amplifying apparatus to which current is supplied through conductors 189 connected to the house-lighting circuit. The anode 74a and cathode 74c of the photo-electric cell 74 are connected by conductors 190 to the amplifying apparatus 188, which utilizes the current fluctuations in circuit 190 to operate or control a loudspeaker 191. At the present time, the most popular loudspeaker is the so-called moving coil type, which utilizes a small cone diaphragm, but any approved form of loudspeaker may be used. The amplifying apparatus 188 may be similar to the well known radio circuits employing detector tubes and amplifying tubes. In this case, the current fluctuations in circuit 190 of cell 74 produced by light variations on cathode 74c 40 constitute the input for the amplifying apparatus 188. These input current variations are sufficiently amplified to operate the loudspeaker 191 with the requisite degree of power and fidelity of tone. A main on-and-off switch 192 may be employed to cut off not only the film-driving motor 139, but also the amplifier 188, so that all circuits are opened and no waste of current is possible. The switch 192 may conveniently be mounted on the top board 12 of the cabinet, or it may be located at a distance from the cabinet, as in a small box that may be placed anywhere. It is understood that the switch 192 is closed to permit operation of the machine through the auxiliary start-and-stop switch lever 162.

55 One end of the shutter-operating coil 119 is connected by conductor 193 to the cathode 75c of the photo-electric cell 75, and the anode 75a of this cell is connected to the positive side of a battery 194 or other source of constant current. The other side of the battery 194 is connected by a conductor 195 to one end of coil 148. The clutch-operating coils 147 and 148 are joined at one end by conductor 196 which is connected by conductor 197 to the other end of coil 119. It is thus seen that coil 119 is connected in series with either of the clutch coils. A conductor 198 connects one side of clutch coil 147 with the negative terminal of a battery 199 or other source of constant current. One side of coil 177 is connected to switch arm 105 by conductor 200, and the other side of that coil leads to conductor 198 through connection 201. A conductor 202 connects the cathode 76c of photo-electric cell 76 to conductor 193, which leads to the shutter-operating coil 119. A wire 203 connects the switch

arm 106 to conductor 202. The anode 76a of cell 76 is connected to the positive side of battery 199. In actual practice, the photo-electric cells 75 and 76 are preferably connected to the house-lighting system (through a rectifier if necessary), and I have shown the batteries 194 and 199 to simplify the circuit connections in Fig. 11.

We shall assume that the film is running off reel 13 onto reel 14 (that is, from left to right in the top portion of Fig. 11), for the playing of the first sound track A. This means that the shutter disk 54 is in the position shown in Fig. 5, with slit a in operative position. The sprocket shafts 127—128 and the reel shafts 152—153 are driven by the electric motor 139 through gear connections 136—134. To prevent possible confusion, I want to explain at this point that the control box 16 is shown diagrammatically at the bottom of Fig. 11 as if we were looking down into the box from a position behind the cabinet. Therefore, while the forward run of the film is from left to right in a front view, this direction becomes right to left in a view from the rear. This accounts for the two "Forward" arrows at the top and bottom of Fig. 11 pointing in opposite directions. As the sound track A moves past the aligned light apertures 45 and 46, the degree or intensity of the light that strikes cathode 74c of photo-electric cell 74 from lamp 71 varies in accordance with the characteristic markings of the sound track. At the present time there are two ways of recording sound on a photographic film: either by varying the intensity of light across a band of uniform width, or by exposing a band to uniform light but varying its width. The sound tracks shown diagrammatically in the drawings are intended to represent any practical method of recording sound or other vibrations on a photographic film. The variations of light on cathode 74c as controlled by the sound track produce electric impulses which are amplified in apparatus 188 for operating the loudspeaker 191. Let us now see what happens when the end of sound track A is reached. Referring to Figs 9 and 10, it will be seen that the film is provided near its ends with apertures or windows 204 and 205, which are located in an opaque band or section 206 of the film. The apertures 204 and 205 may be holes punched in the film, or they may simply be transparent spots in the opaque band 206, which runs between the middle sound tracks B and C. If the entire area of the film outside the sound tracks is made opaque, no separate band 206 is necessary. When the end 63 of sound track A is reached in its operative field, the window 205 is in line with aperture 85 in the control box, so that light rays from lamp 71 strike the cathode 75c of photo-electric cell 75. This closes the circuit through coils 119 and 148 as follows: starting at the plus side of battery 194, across the electronic conducting space 75—75c of cell 75, conductor 193, coil 119, conductor 197, coil 148, and through conductor 195 back to the battery. Coil 119 on being energized, operates the shaft 52 and moves the shutter disk 54 to bring slit B into operative position for sound track B, which begins at 65 (see Fig. 10.) The operating connections between coil 119 and shaft 52 have already been explained, so need not be repeated. The movement of shutter disk 54 is accompanied by a like movement of contact disk 103, which is fixed on shaft 52. Disk 103 is moved through an angle indicated by the division marks in Fig. 11, each movement in the present instance being one-twelfth of a revolution. I

- might explain here that the arrow associated with the shutter disk 54 in Fig. 5 points in the opposite direction to the arrow of contact disk 103 in Fig. 11. Those two disks always rotate in the same direction, but we are looking at the shutter disk in Fig. 5 from the front of the cabinet, while in Fig. 11 the contact disk 103 and locking wheel 98 are viewed from the opposite direction.
- 10 When the coil 148 is energized at the end of sound track A, it throws the clutch ring 143 against the bevel gear 135 to reverse the rotation of sprocket shafts 127-128 and reel shafts 152-153. The film now runs in the direction of arrow 64 (see Fig. 10) for the playing of the second sound track B, and is wound off reel 14 onto reel 13. When the end of sound track B is reached the window 204 in film 15 is in line with aperture 86 in the control box and light from lamp 71 strikes the cathode 76c of photo-electric cell 76. This closes the circuit of battery 199 through coils 119 and 147 as follows: starting at the positive side of battery 199, across the electronic conducting path 76a-76c of cell 76, conductors 202 and 193, coil 119, conductor 197, coil 147, and through conductor 198 back to the battery. Coil 119 again gives the shutter disk 54 a kick forward to bring slit c into line with the third sound track C, which begins at 67 (see Fig. 9). At the same time, the contact disk 103 is moved through another one-twelfth of a revolution. When the coil 147 is energized, it shifts the clutch ring 143 back into engagement with bevel gear 134, so that now the film is wound off reel 13 onto reel 14 for the playing of the third sound track C.
- When the end 68 of sound track C is reached, the window 205 of the film registers with aperture 85 in control box 16 and the photo-electric cell 75 is activated by light rays from lamp 71 to close the circuit of battery 194 through the shutter-actuating coil 119 and the clutch-operating coil 148. As these circuits were traced in connection with sound track A, it will not be necessary to repeat them here. The third kick received by the shutter disk 54 brings slit d in line with the last record track D. When slit D moves into operative position, the switch arms 105-106 engage one of the contact pieces 104 of disk 103. This, however, does not close the circuit of battery 199 through coil 177, because the photo-electric cell 76 is inactive until the end of track D is reached. During the playing of the fourth record track D, the film is wound off reel 14 onto reel 13, which is the initial pay-out reel.
- 55 When the end 70 of sound track D is reached, the window 204 of the film is in line with aperture 86 in control box 16 and light from lamp 71 strikes the cathode 76c of cell 76. The circuit of battery 199 is now closed again through coils 119 and 147, as previously explained. This fourth kick of the shutter disk 54 brings slit a of the next set of slits into line for playing the first record track A of the next film. The energizing of coil 147 moves the clutch ring 143 into engagement with bevel gear 134. Consequently, when the next film is inserted in the machine, the driving connections are in condition to wind the film off reel 13 onto reel 14, so that no adjustments are necessary by the operator.
- 70 At the end of the last sound track D, the circuit of battery 199 is closed through coil 177, because the switch members 105 and 106 are connected by one of the contact pieces 104. The energized coil 177 opens the motor switch 171-180, as already described in detail in connection with Fig. 15. The film is thus automatically stopped when the end of the last sound track is reached. The motor switch 171-180 remains open because the arm 174 is locked in down position by the latch member 170. To start the motor again, it is only necessary to move the finger piece 162 into position 162b, as previously explained. The short strip of film that may remain between the reels 13 and 14 after the last sound track has been played, is readily wound by hand onto reel 13 before the latter is removed from the machine. A shelf 207 in the cabinet may be used for holding a supply of additional reels 208.
- 15 In Fig. 16 I use two separate buttons 209 and 210 for starting and stopping the motor by means of switch 171-180. Those parts of Fig. 16 that correspond to similar parts in Fig. 15 are indicated by like reference numerals, so that a portion of the description of Fig. 15 is also applicable to Fig. 16. The latch member 170 has a bevelled extension 211 arranged in the path of the bevelled lower end 212 of the "start" button 209. The arm or lever 174 is directly below the "stop" button 210, which may also form a stop for the upward movement of the arm by spring 178. Coil springs 213 normally hold the push buttons 209 and 210 in upper position. When the "start" button 209 is pushed down, latch member 170 is moved into releasing position 170'. If the solenoid arm 174 was held in down position by member 170, it will now be released and moved up to normal position under the action of spring 178, so that the motor switch 171-180 is closed, as explained in connection with Fig. 15. When the "stop" button 210 is depressed, the arm 174 is forced down into the position shown in full lines in Fig. 16 to open the motor switch 171-180, so that the machine stops playing. The arm 174 is held locked in down position by the latch member 170, whereby the motor circuit remains open until the "start" button 209 is depressed. The downward movement of buttons 209 and 210 is limited by the annular shoulders 214 in top board 12 and the collars 215 on the buttons. In some respects the double button arrangement of Fig. 16 for starting and stopping the machine is preferable to the single finger piece 162 of Fig. 15. It will be observed that the buttons may be released immediately after being fully depressed.
- 40 In the modification of Fig. 17, the motor switch 171-180 is controlled electrically by a pair of push buttons 216 and 217, which may be mounted at any convenient point on the cabinet, usually on the top board. The "start" button 216 is mounted on a spring arm 218 adapted to engage a stationary contact member 219 for closing the circuit of battery 220 through a solenoid 221. A conductor 222 connects one side of battery 220 with switch contact 219, and a conductor 223 leads from one side of coil 221 to the movable switch arm 218. The other side of coil 221 is connected at 224 to the battery lead 225. The "stop" button 217 is mounted on a spring arm 226 which is connected by a conductor 227 to one side of coil 221. The other side of this coil goes to the battery lead 225. A conductor 228 connects one side of battery 220 with a stationary contact 229 associated with switch arm 226. The free end of arm 174 engages a reversely bevelled catch 230 of a spring arm 231. The catch 230 is so shaped that it holds the arm 174 frictionally in either

position and yet permits the same to move into the other position. In other words, the catch 230 releasably holds the arm 174 in raised position to keep the motor switch 171-180 closed, 5 or in lowered position 174' to keep the motor switch open.

Still referring to Fig. 17, when the "start" button 216 is pushed down, the circuit of battery 220 is closed through coil 221 which pulls the 10 arm 174 up to close the motor switch 171-180. This switch remains closed until the "stop" button 217 is pushed down to energize coil 177, which pulls the arm 174 down to break the motor switch 171-180. The "start" and "stop" 15 buttons 216 and 217 need only be held down for an instant to start the machine and stop it whenever desired. The manual control of the motor switch by means of the buttons 216 and 217 is independent of the automatic stopping 20 of the motor when the end of the last sound track is reached. The purpose of the finger piece 162 in Fig. 15 and the "start" and "stop" buttons in Figs. 16 and 17 is to enable a person to stop the machine at any time and to start it again when desired. In actual practice, coil 221 will be connected to the house-lighting system when plug 184 (see Fig. 11) is inserted. The battery 220 is shown merely to simplify the 25 circuit connections in the drawings.

30 Although I have shown a single lamp 71 for controlling the operation of cells 74, 75 and 76, it is evident that a separate lamp may be used for each cell, thus dispensing with the mirrors 35 78 and 79. Referring to Fig. 3, the path of light rays has been diagrammatically indicated without taking into account the use of lenses ordinarily employed in concentrating the light and directing it properly against the light-sensitive 40 electrode of each cell. Since the use of such lenses in optical recording and reproducing systems is well understood, I have omitted them to simplify the drawings and specification. Instead of supporting the film reels 13 and 14 on the top board of the cabinet, I may mount them 45 on a vertical panel behind the doors 17, with a corresponding re-arrangement of the control box and driving connections. I think, however, that the reels are manipulated most easily by mounting them on the top board, as shown in Fig. 1. 50 The shutter 54 may be in the form of an endless band having the proper slits and intermittently movable in the direction of its length, but I prefer a rotary disk because it is easier to mount and simpler to operate. This disk may also be 55 used with a film having only two sound tracks. The photo-electric control of the motor connections and shutter 54 by the film itself has a decided practical advantage, because no movable parts or switch-operating members are in 60 mechanical contact with the film. This eliminates wear on the film and injury to its sensitized surface.

65 It will be clear from the foregoing description that I have provided a phonograph in which a film with a multiple sound track is played continuously from the beginning of the first track to the end of the last track without attention by the operator. The interruptions between the ending 70 of one track and the starting of the next are so short as to be barely perceptible, so that the playing is practically continuous. If a musical composition is recorded, the intervals of jumping from one track to the next may be pauses in 75 the music, so that even these brief interruptions would not be noticed. Of course, it is not neces-

sary that all the tracks shall relate to the same subject matter. For example, track A may be an 5 orchestral number, track B a speech, track C a song, and so forth. The number of tracks recorded on a film obviously depends on the available width of film and on the individual width of the tracks. It is doubtless possible to make a 10 sound film with six or eight record tracks and of such length as to play continuously for several hours without attention by anybody. Such long 15 playing films may bear the complete score of musical compositions of great length, which heretofore had to be abbreviated on phonograph records. It is also feasible to record complete 20 operas, plays and books on films in accordance with 25 my invention. While I prefer an even number of record tracks on a film, an odd number (like 3, 5, etc.) may be used; but an even number of tracks brings the film back to initial position at the conclusion of the run. If a person happens 30 to be out of the room when the end of the last sound track is reached, the film is automatically stopped and the motor circuit remains open until somebody moves the switch to starting position. Although the apparatus shown in the drawings 35 has been described for the reproduction of sound from the film, I want it understood that the same or similar apparatus can be employed for recording on the film.

30 My invention is by no means limited to house- 30 hold phonographs, and I may say it finds particular usefulness in the field of talking movies. Two methods of sound accompaniment for motion pictures are employed at the present time: 35 in the phonographic method, the sound is reproduced from a wax record operated in synchronism with the picture; in the optical method, the picture film carries a sound track along one edge. The maximum playing time of a large-sized wax record is about twelve minutes, which is usually 40 less than the running time of a standard-length picture reel. Hence, the necessity of changing from one record to another while the picture is on. This requires either a special attendant or 45 automatic switching mechanism of great cost. Recording the sound alongside of the picture on the same film is objectionable for several reasons, principally because the sound track usually requires different treatment during exposure, developing and printing of the film than the picture 50 itself. Now, the multiple-track film of my invention can carry the sound accompaniment for several reels of pictures. To illustrate: a standard motion picture film has a length of about 55 900-1000 feet, and the regulation number of reels is five for a feature picture. These pictures usually run for one hour and a quarter. A single 1000-foot film with six record tracks has an acoustic 60 capacity for a talking movie of five or six reels, and it is possible to go beyond that.

60 Although I have shown and described a specific machine, I want it understood that my invention is not limited to the details set forth. It is to be expected that changes and modifications will occur to others in the construction of 65 machines in accordance with my invention, because the basic features of this invention are susceptible of mechanical embodiment in other ways than herein set forth by way of illustration. In a less efficient form of my invention, certain 70 features may be used without others. As far as I know, I am the first to provide a recording or reproducing machine in which a photographic film has more than two sound tracks running in alternately opposite directions, in combination 75

with means whereby the sound tracks are automatically recorded or played as a substantially continuous track, and I claim this idea in a fundamental way.

5. I claim as my invention:

1. In optical apparatus utilizing a film which has a plurality of record tracks, a rotary member having a plurality of light apertures movable in an endless path, means whereby only one track 10 can be exposed to said apertures at a time, each aperture being arranged in operative relation to one of said tracks, means for positively locking said member in each operative position, an electromagnetic device for operating said member, 15 and connections whereby said device when energized actuates said locking means to releasing position before operating said member.

2. In acoustic apparatus, the combination of a film having a plurality of reversely arranged 20 sound tracks, a source of light and a photo-electric element arranged on opposite sides of said film in operative relation thereto, mechanism for driving said film forwardly and reversely, a movable shutter for exposing only one track at a 25 time to light rays from said source, and photo-electric means optically controlled by the film for operating said shutter, said photo-electric means including a light-sensitive cell and a beam of light sent thereto through the film in a direction substantially at right angles to the face of the 30 film.

3. In optical apparatus utilizing a film with a photographic record thereon, the combination of means for supporting a length of said film for 35 operative movement in an optical field, mechanism for driving said film, a photo-electric cell, means for sending a beam of light to said cell in a direction substantially at right angles to the plane of movement of the film in the optical 40 field, said cell and film being so arranged that the film moves flatwise across the path of said light beam, means on the film adapted to act upon said light beam when a point on the moving film reaches a predetermined position to affect 45 the condition of said cell, and an electric circuit controlled by the affected cell for automatically stopping said driving mechanism, which remains inoperative so that the film is held stationary.

4. In optical apparatus utilizing a film with a photographic record thereon, the combination of 50 a pair of reels for supporting a length of said film for operative movement in an optical field, reversible mechanism for driving said film in opposite directions for unwinding and rewinding, 55 a photo-electric cell, means for sending a beam of light to said cell in a direction substantially at right angles to the plane of movement of said film in the optical field, said cell and film being so arranged that the film moves flatwise across the 60 path of said light beam, means on the film adapted to act upon said light beam when a point on the unwinding film reaches a predetermined position to affect the condition of said cell, and 65 electric means controlled by the affected cell for automatically reversing said driving mechanism to rewind the film on its original reel.

5. In optical apparatus utilizing a film with a photographic record thereon, the combination of 70 a pair of reels for supporting a length of said film for operative movement in an optical field, reversible mechanism for driving said film in opposite directions for unwinding and rewinding, 75 a pair of photo-electric cells, means for sending a separate beam of light to each cell in a direc-

tion substantially at right angles to the plane of movement of said film in the optical field, the two cells and the film being so arranged that the film moves flatwise across the path of each light beam, means on the film adapted to act upon one 5 of said light beams when the film has been unwound to affect the condition of one of said cells, an electric circuit controlled by the affected cell for automatically reversing said driving mechanism to rewind the film, other means on the film 10 adapted to act upon the second light beam when the film has been rewound to affect the condition of the second cell, and means whereby the second cell when so affected automatically stops the 15 driving mechanism.

6. In film-controlled optical apparatus of the class described, an intermittently rotatable shutter having a series of slits and covered on one side with soft material, and means for supporting a moving film substantially in contact with the 20 covered side of said shutter.

7. The combination of a film supported for operative movement and having a plurality of record tracks, optical reproducing mechanism associated with said film, a rotary shutter disk 25 having slits for exposing only one track at a time to said mechanism, said disk being mounted substantially in contact with one side of the film, the contacting side of said disk being covered with soft material to prevent injury to the film. 30

8. In film-controlled optical apparatus of the class described, a rotary shutter arranged to occupy a plurality of operative positions, means for positively locking the shutter in each operative 35 position, and electromagnetic means for automatically actuating said locking means to releasing position at predetermined intervals.

9. In film-controlled optical apparatus of the class described, a movable shutter arranged to occupy a plurality of operative positions, film- 40 controlled mechanism for moving said shutter at predetermined intervals from one position to the next, means for positively locking the shutter in each operative position, and means operated by said mechanism for releasing said locking means. 45

10. In film-controlled optical apparatus of the class described, a rotary shutter arranged to occupy a plurality of operative positions, electromagnetic mechanism for rotating said shutter at predetermined intervals from one position to the 50 next, means for positively locking the shutter in each operative position, and means controlled by said mechanism for releasing said locking means.

11. In apparatus of the class described, a movable shutter having a plurality of light apertures 55 so arranged that only one aperture at a time is in operative position, connections for actuating the shutter from one position to the next, means independent of said connections for automatically locking the shutter in actuated position, and 60 means controlled by said connections for releasing said locking means before the shutter is actuated.

12. In acoustic apparatus, the combination of a film having a plurality of sound tracks, an electric motor for operating said film, optical reproducing mechanism associated with said film, means controlled by the film for successively exposing said tracks one at a time to said mechanism, said means including a movable member 65 automatically operated when a new track is played, a switch closed by said member when the last track is reached, and circuit connections controlled by said switch for automatically deener- 70

75

- gizing said motor and stopping the film when the last track has been played.
13. In acoustic apparatus, the combination of a film having a plurality of sound tracks, an electric motor for operating said film, optical reproducing mechanism associated with said film, a movable shutter for successively exposing said tracks one at a time to said mechanism, an electromagnet energized at predetermined intervals to operate said shutter from one position to the next, a movable member operated whenever said electromagnet is energized, a switch closed by said member when the last track is reached, and circuit connections controlled by said switch for automatically de-energizing said motor and stopping the film when the last track has been played.
14. In apparatus of the class described, the combination of means for operatively supporting a moving film, an electric motor for driving said film, a switch in the motor circuit, means controlled by the film for opening said switch at a predetermined moment, said switch remaining in opened condition, and a manually operable member for closing said switch at will independently of the film.
15. In acoustic apparatus, the combination of a record member, reproducing means controlled by said member, an electric motor for operating said member, a switch in the motor circuit, electromagnetic means controlled by said record member for automatically opening said switch to stop the motor when said member is played through, and manually operable means for closing the opened switch to start the motor and operate said record member.
16. In acoustic apparatus, the combination of a record member, reproducing means controlled by said member, an electric motor for operating said member, a switch in the motor circuit, electromagnetic means controlled by said record member for automatically opening said switch to stop the motor when said member is played through, and a hand-operable switch for energizing said electromagnetic means independently of said record member to open the motor switch at will, said motor switch remaining in either position until actuated to the other position.
17. In acoustic apparatus, the combination of a record member, reproducing means controlled by said member, an electric motor for operating said member, a switch in the motor circuit, electromagnetic means controlled by said record member for automatically opening said switch to stop the motor when said member is played through, manually operable means for closing the opened switch to start the motor and operate said record member, and connections whereby said manually operable means is adapted to open the closed switch independently of said electromagnetic means.
18. In acoustic apparatus, the combination of a record member, reproducing means controlled by said member, an electric motor for operating said member, a switch in the motor circuit, electromagnetic means controlled by said record member for automatically opening said switch to stop the motor when said member is played through, manually operable means for closing the opened switch to start the motor and operate said record member, a push button for closing the opened switch, a second push button for opening the closed switch, and means whereby said switch remains in either position until actuated to the other position.
19. In optical apparatus utilizing a film which has a plurality of record tracks, a movable shut-
- ter for exposing only one track at a time to a field of light, mechanism controlled by said record tracks, means for moving said film past said shutter, said means including an electric motor, a member movable with said shutter, a normally open switch closed by said member when the shutter is in position for the last record track, a second normally open switch in series with said other switch and adapted to be closed when the end of the last track is reached, an electromagnetic device energized by the closing of both of said switches, and means for stopping the motor when said device is energized.
20. In acoustic apparatus, the combination of means for operatively supporting a film provided with a plurality of sound tracks running in alternately opposite directions, an electric motor having connections for operating said film in both directions, optical reproducing means associated with said film, a movable shutter for exposing only one track at a time to said mechanism, means controlled by the film for automatically operating said shutter and reversing said driving connections at the end of each sound track, a switch in the motor circuit independent of said reversing connections, and electromagnetic means automatically energized when the end of the last track is reached to open the motor switch.
21. In acoustic apparatus, the combination of means for operatively supporting a film provided with a plurality of sound tracks running in alternately opposite directions, reproducing mechanism associated with said film, an electric motor for driving said film in opposite directions, means for subjecting said mechanism to the control of only one sound track at a time, film-controlled connections for automatically reversing the operation of said motor at the end of each track, a separate switch independent of said reversing connections, means for closing said switch when the end of the last track is reached, and an electromagnetic device energized by said closed switch to open the motor circuit.
22. In acoustic apparatus, the combination of a record member, reproducing means controlled by said member, an electric motor for operating said member, a switch in the motor circuit, electromagnetic means controlled by said record member for automatically opening said switch to stop the motor when said member is played through, a hand-operable switch for energizing said electromagnetic means independently of said record member to open the motor switch at will, said motor switch remaining in either position until actuated to the other position, other electromagnetic means for closing the motor switch to start the apparatus, and a second hand-operable switch for energizing said last-mentioned electromagnetic means, said motor switch remaining in either position until actuated to the other position.
23. In film-controlled apparatus, the combination of a pair of reels for supporting a film for movement lengthwise in alternately opposite directions, an electric motor in reversible driving relation to said film, means for automatically reversing the driving movement of said motor when the film is unwound from its original reel, other means for automatically reversing the driving movement of said motor when the film is rewound on its original reel, each of said reversing means including an electromagnetic device and a photoelectric cell for controlling said device, means whereby one of said cells is con-

trolled when the film moves in one direction, and means whereby the other cell is controlled when the film moves in the other direction.

24. The combination of means for supporting a length of phonographic film for movement in opposite directions, reversible driving connections for said film, photoelectric means controlled by the film when unwound for reversing said connections, and other photoelectric means controlled by the film when rewound for again reversing said connections, each of said photoelectric means including a beam of light in the path of the moving film and substantially at right angles to the face of the film.

15 25. In sound-reproducing apparatus, the combination of means for operatively supporting a length of film having a sound track thereon, driving connections for said film, optical reproducing mechanism associated with said film and controlled by the sound track thereon, and photoelectric means independent of said mechanism and controlled by the film itself in normal operative condition for controlling said driving connections, said photoelectric means including a beam of light in the path of the moving film and substantially at right angles to the face of the film.

26. In acoustic apparatus, the combination of means for operatively supporting a film provided with a plurality of sound tracks running in alternately opposite directions, driving connections for said film, optical reproducing mechanism associated with said film, and means optically controlled by said film in normal operative condition for automatically reversing said driving connections when the end of a record track is reached, said reversing means including photoelectric means separate from said reproducing mechanism, and said photoelectric means including a beam of light in the path of the moving film and substantially at right angles to the face of the film.

27. In film-controlled apparatus, the combination of means for supporting a film for movement lengthwise in alternately opposite directions, means for automatically reversing the film when unwound, means for automatically reversing the film when rewound, each of said reversing means including a photoelectric cell optically controlled by the film itself in normal operative condition, and means controlled by one of said photoelectric cells for automatically stopping the film in rewound condition after it has been reversed a predetermined number of times.

55 28. In apparatus of the class described, the combination of means for supporting a film for operative movement, said film having at least four sound tracks running in alternately opposite directions, optical reproducing mechanism associated with said film, a movable shutter for exposing only one track at a time to said mechanism, driving connections for automatically reversing the movement of said film at the end of

each record track, an electromagnetic device for automatically operating said shutter wherever said driving connections are reversed, each movement of the shutter exposing the next record track to said mechanism, a photoelectric cell independent of said optical reproducing mechanism and controlled by the film in normal operative condition for controlling said device, and means for sending a beam of light through the film to said cell in a direction substantially at right angles to the face of the film.

29. In acoustic apparatus, the combination of means for operatively supporting a film provided with a plurality of sound tracks running in alternately opposite directions, driving connections for said film, optical reproducing mechanism associated with said film, means optically controlled by said film in normal operative condition for automatically reversing said driving connections when the end of a record track is reached, said reversing means including two photoelectric cells independent of said reproducing mechanism, one cell being arranged to cause unwinding of the rewound film, and the other cell being arranged to cause rewinding of the unwound film, and means for sending a beam of light through the film to each cell in a direction substantially at right angles to the face of the film.

30. In acoustic apparatus, the combination of means for operatively supporting a film provided with a plurality of sound tracks running in alternately opposite directions, driving connections for said film, optical reproducing mechanism associated with said film, means optically controlled by said film for automatically reversing said driving connections when the end of a record track is reached, said reversing means including two photoelectric cells independent of said reproducing mechanism, one cell being arranged to cause unwinding of the rewound film and the other cell being arranged to cause rewinding of the unwound film, and a single source of light for optically energizing said reproducing mechanism and both of said cells.

31. In film-controlled acoustic apparatus, the combination of means for supporting a film having a plurality of sound tracks running in alternately opposite directions, reversible driving connections for said film, photo-electric reproducing mechanism controlled by said mechanism, means for holding said film, and mechanism against relative lateral displacement, a rotary shutter for exposing only one track at a time to said mechanism, a switch controlled by the film itself at the end of each sound track, electromagnetic means energized by the operation of said switch for operating said reversing connections and said shutter, and other electromagnetic means automatically controlled by the film at the end of the last track to stop said driving connections.

ADOLPH A. THOMAS.
